The ornamental design for a infrared control panel for actuating a flush mechanism, as shown and described.

DESCRIPTION

FIG. 1 is a front view of the control panel;

FIG. 2 is a bottom view of the control panel of FIG. 1;

FIG. 3 is a top view of the control panel of FIG. 1;

FIG. 4 is a right side view of the control panel of FIG. 1;

FIG. 5 is a left side view of the control panel of FIG. 1;

FIG. 6 is a back view of the control panel of FIG. 1;

FIG. 7 is a back perspective view of the control panel of FIG. 1; and,

FIG. 8 is a front perspective view of the control panel of FIG. 1.
